US00D843389S

(12) **United States Design Patent** (10) **Patent No.:** **US D843,389 S**
Protzman et al. (45) **Date of Patent:** **** Mar. 19, 2019**

(54) **DISPLAY SCREEN OR PORTION THEREOF WITH SET OF GRAPHICAL USER INTERFACES**

(71) Applicant: **Lutron Electronics Co., Inc.**,
Coopersburg, PA (US)

(72) Inventors: **Brent Protzman**, Easton, PA (US);
Michelle L. Greene, Bethlehem, PA (US); **Erica L. Clymer**, Northampton, PA (US); **Jennifer Wong**, Breinigsville, PA (US); **Laura Marie Friedlander**, Harleysville, PA (US); **Joseph Roy Parks**, Emmaus, PA (US); **John N. Callen**, Center Valley, PA (US)

(73) Assignee: **Lutron Electronics Co., Inc.**,
Coopersburg, PA (US)

(**) Term: **15 Years**

(21) Appl. No.: **29/642,773**

(22) Filed: **Apr. 2, 2018**

Related U.S. Application Data

(63) Continuation of application No. 29/587,123, filed on Dec. 9, 2016, now Pat. No. Des. 815,114, and a continuation of application No. 29/525,156, filed on Apr. 27, 2015, now Pat. No. Des. 776,151.

CLAIM

The ornamental design for a display screen or portion thereof with set of graphical user interfaces, as shown and described.

DESCRIPTION

The sole FIGURE shows two portions of a display screen with set of graphical user interfaces showing our new design.

The dashed broken lines illustrate a display screen or portion thereof, and form no part of the claimed design.

The bracket shows a set of graphical user interfaces, and forms no part of the claimed design. The graphical user interfaces are arranged as shown for convenience of illustration; the relative arrangement of graphical user interfaces forms no part of the claimed design.
